UNITED STATES PATENT OFFICE.

WILLIAM A. JONES, OF TOLEDO, OHIO, ASSIGNOR OF ONE-HALF TO THE SWIGART OPTICAL COMPANY, OF SAME PLACE.

DESIGN FOR AN EYEGLASS-GUARD.

SPECIFICATION forming part of Design No. 35,094, dated September 17, 1901.

Application filed April 18, 1901. Serial No. 56,515. Term of patent 7 years.

To all whom it may concern:

Be it known that I, WILLIAM A. JONES, a citizen of the United States, residing at Toledo, Lucas county, Ohio, have invented and produced a new and original Design for Eye-glass-Guards, of which the following is a specification, reference being had to the accompanying drawing, forming part hereof.

The figure illustrates in perspective an eye-glass-guard showing my new design.

As shown in the drawing, the leading or material feature of my design consists of a plate *a*, having at top an arm *b*, projecting downwardly and outwardly in the same plane with the plate, the plate being somewhat curved toward its lower end. At its outer extremity the arm *b* has rigidly secured thereto a circular pad-plate *c*. At bottom the plate *a* has an arm *d* lying in the same plane with the plate *a*, the arm being curved downwardly and outwardly and having rigidly attached to its outer extremity a pad-plate *e*, which is an elongated rectangle in outline, as illustrated. The two pads *c e* lie substantially in

the same curved or bent plane as the plate *a*; 25 but the pads carried by the upper and lower arms are at unequal distances from the plate *a*, the round pad on the upper arm being at a greater distance from the plate *a* than the rectangular pad *e* on the lower arm. Dis- 30 posed longitudinally and centrally of the plate *a* is a series of adjusting-holes *f f*.

It is obvious that the design here described is equally applicable to right-hand and to left-hand guards.

Having described my invention, what I claim as new, and desire to secure by Letters Patent, is—

The design for an eyeglass-guard, as herein shown and described.

In testimony whereof I have signed my name to this specification in the presence of two subscribing witnesses.

WILLIAM A. JONES.

In presence of—

L. E. BROWN,
F. M. DOTSON.
